E. F. PRICE,
BOOKBINDER'S SIGNATURE HOLDING CLAMP.
APPLICATION FILED APR. 8, 1914.

Patented Nov. 24, 1914.

UNITED STATES PATENT OFFICE.

EDWIN F. PRICE, OF WASHINGTON, DISTRICT OF COLUMBIA.

BOOKBINDER'S SIGNATURE-HOLDING CLAMP.

1,118,581.

Specification of Letters Patent. Patented Nov. 24, 1914.

Application filed April 8, 1914. Serial No. 830,410.

To all whom it may concern:

Be it known that I, EDWIN F. PRICE, a citizen of the United States, residing at Washington, in the District of Columbia, have invented new and useful Improvements in Bookbinders' Signature-Holding Clamps, of which the following is a specification.

My invention relates to a signature holding clamp for book binders' use, to enable a signature and guard to be readily sewed together by hand.

I have found that with a device such as is hereinafter described, a ledger may be more quickly and accurately sewed by hand than by a machine such as is in common use. With machine sewing the ledger sheets are first folded to form a central crease as a guide for positioning the guard, and after the latter is placed thereon, they are passed together through the sewing machine; but I have found that it is difficult to prevent the separate sheets from moving with respect to each other and also to keep the guard centrally positioned. In machine sewed ledgers the threads must be tied at both ends of the line of stitching. In my device the ledger sheets and the guard are accurately positioned and firmly held so that they may be sewed together in such a manner that it is only necessary to tie the threads at one end of the line of stitching. In actual tests I have sewed a greater number of signatures and guards in a given time than can ordinarily be done with a sewing machine and the work is much more accurate.

My invention consists in the features hereinafter described and particularly pointed out in the appended claims.

Referring to the drawing furnished and forming part of this specification, Figure 1 is a front elevation of a clamp embodying my invention. Fig. 2 is a side view thereof. Fig. 3 is a top or plan view of the clamping members and a portion of the supporting work-board. Fig. 4 is an enlarged detail sectional view taken on line 4-4 of Fig. 1 showing the ledger leaves and guard between the clamping members.

As illustrated in the drawings, A and B indicate clamping members between which the signature or ledger leaves, and the guard to which they are to be stitched, are clamped. These clamping members will ordinarily be made of a sufficient length to support ledger

leaves of the largest size in an upright position. Said clamping members are hinged together at one end in any suitable manner, but I prefer to hinge them by means of links ⁶⁰ a which are inserted in slots cut in one end of each of said clamping members and secured thereto by means of pins a' as clearly illustrated in Figs. 1 and 3. At the opposite end of the clamping member B there is a link b pivotally secured to a plate b' fastened to the rear of said clamping member B, and the free end of said link b is provided with a screw-threaded shank b² for the reception of a thumb nut b³. The clamping ⁷⁰ members A and B are each provided with a slot a² into which the link b is swung when the clamping members A and B are closed, the thumb nut b³ on said link being turned to secure the clamping members in clamping ⁷⁵ relations, as will be readily understood. After the thumb nut b³ has been initially set to hold the clamping members together with required pressure, the adjustment need not be thereafter disturbed, as the link b may be ⁸⁰ readily swung out of engagement with the member A to open the clamping members as illustrated in Fig. 3.

The clamping member B is secured to one end of a work-board C which is preferably ⁸⁵ made the full width of the clamping member B and which extends rearwardly therefrom a sufficient distance to afford support for the clamping members when the device is placed on a bench or table, indicated in ⁹⁰ dotted lines in Fig. 2, and also to form a clear working space on which the ledger leaves may be flatly folded after they have been sewed to the guard as will be herein-after explained. The work-board C is pref- ⁹⁵ erably made in two separable sections c and c' secured together in any suitable manner when the device is in use, but which may be separated for storage when the device is out of use. As illustrated in the ¹⁰⁰ drawing the two sections c and c' are secured together by dowels c² and links c³, the latter being pivotally secured to the section c by means of screw c⁴ and having a hooked end which is swung over screws c⁵ in the sec- ¹⁰⁵ tion c'.

At the front edge of the work-board C, and in alinement with the clamping member B, are two depending arms d, d', said arms being longitudinally slotted as at d² for the ¹¹⁰ reception and adjustment of the signature rests D. These rests are slidably mounted

in the slots d^2 and are secured in adjusted position by means of thumb screws d^3 , in a well known manner. It will be understood that the signature or ledger leaves are placed in upright position between the clamping members A and B with the lower edge thereof resting on the rests D, and in order that the leaves may be held laterally to prevent buckling, I provide the clamping member A 10 with depending arms or rods e, e . Said arms are bent at their upper ends to form crank arms e' which are pivotally secured at their outer ends to the underside of the clamping member A by screws e^2 , as clearly shown in 15 Fig. 1. At their lower ends said arms pass their apertures in the rests D. The crank bends e' in the upper ends of the arms e, e permit the clamping members A and B to be opened a limited distance sufficient for the 20 insertion and removal of the ledger leaves, said arms being rotated by the opening and closing movement of the clamp, as will be readily understood.

For limiting the movement of the clamping member A, I provide a stop f which is 25 secured to the under side of the member A, and which projects beneath the member B, the rear end of the stop being turned up to engage the clamping member B and thus 30 limit the opening movement of the member A, as will be readily understood.

An adjustable stop G is mounted upon the clamping member B adjacent the hinged end thereof, said stop being in the form of 35 a flat metal plate provided with a slot g . A screw g' passing through said slot and into the clamping member B serves to hold the stop G in adjusted position. The forward end of said stop projects over the 40 opening between the two clamping members and serves as a guide for positioning the signature or ledger leaves. It will be noted that the upper edges of the clamping members A and B are provided with spaced 45 notches h which serve to guide the operator in properly spacing the stitches, as will be hereinafter described.

When in use, the device is placed upon a bench or other support with the work-board 50 resting flatly thereon, and with the depending arms close to the edge of the bench as shown in Fig. 2. The operator, after selecting the requisite number of sheets or leaves, places them in upright position between the 55 clamping members A and B with the lower edges of the sheets resting upon the rests D D and with the right hand edges of the sheets in contact with the stop G as indicated by the dotted line J in Fig. 2. The rests 60 D D are adjusted so that the upper edge of the clamping members will be in alinement with the central line on which the leaves are to be folded. This adjustment, when once made, remains the same for all sheets of a 65 given size. After the sheets have been po-

sitioned, as described, a guard I, (see Fig. 4) which has been centrally folded or creased, is placed between the sheets and the clamping member B, the crease or fold enabling the guard to position itself with respect to the edge of the clamping member B, one-half of the guard dropping between said clamping member and the sheets until the other or folded portion of the guard rests on the upper edge of the clamping 75 member, as illustrated in Fig. 4.

The clamping members A and B are then pressed together and secured in clamping relation by means of the link b, hereinbefore described. The operator then punches holes 80 through the leaves and guards with an awl or other suitable tool, these holes being made along the upper edge of the clamping members, the notches h serving as guides for the awl and for the proper spacing of the holes. 85 The leaves and guard are now sewed together with needle and thread which is passed alternately back and forth through the punched holes, from one edge of the sheets to the opposite edge and then back 90 to the starting point, so that the two ends of the thread will be at one end of the line of stitching, which ends are then tied together. The upper portion of the signature or leaves is then bent forwardly over the edge of the 95 clamping member A, a suitable tool being drawn over said edge to crease the paper along the stitched line. The signature is thereafter removed from the clamp, and laid on the work-board C and flatly folded along 100 the creased line. The operation is repeated for each signature.

Having described my invention, what I claim as new and desire to secure by Letters Patent, is—

1. A signature holding clamp comprising a pair of clamping members for receiving and holding a signature in upright position, each of said members being provided with depending arms affording lateral supports, 110 and a rest engaging said arms and adjustable thereon.

2. A signature holding clamp comprising a pair of clamping members hinged together at one end, means for clamping the members together at the opposite end, each of said clamping members being provided with depending arms affording lateral supports, and rests engaging said arms and adjustable thereon.

3. A signature holding clamp comprising a work-board, a clamp member secured to one edge thereof, a second clamp member pivotally secured to one end of the first mentioned clamp member, clamping means at 125 the opposite end of said clamp members, depending arms depending from each of said clamping members, and forming lateral supports for a signature placed between said members, rests engaging said depend- 130

ing arms and adjustable thereon to form supports for the lower edge of the signature, substantially as described.

4. A signature holding clamp comprising a pair of clamping members hinged together at one end, clamping means at the opposite end of said members, arms depending beneath one of said clamping members, adjustable rests carried by said arms, arms depending from the other of said clamping members slidably connected to said rests, substantially as described.

5. A signature holding clamp comprising a pair of clamping members hinged together at one end, clamping means at the opposite end of said members, arms depend-

ing beneath one of said clamping members, rests slidably mounted on said arms, arms depending from the other of said clamping member and slidably engaging said rests, 20 said arms being bent at their upper ends to form crank extensions, said extensions being pivotally secured to said clamping member, substantially as described.

In testimony whereof I have hereunto set 25 my hand in presence of two subscribing witnesses.

EDWIN F. PRICE.
